UNITED STATES PATENT OFFICE

JOHATHAN EDMUND BROWNING, OF OGDEN, UTAH, ASSIGNOR TO J. E. BROWNING COMPANY, OF OGDEN, UTAH, A CORPORATION OF UTAH

AUTOMATIC FIREARM

Application filed January 28, 1931. Serial No. 511,741.

This invention is applicable to a shoulder arm of rifle caliber and I have shown such a firearm so constructed as to require the manual operation of the trigger to effect the firing of each shot. In regard to this latter feature, however, I do not necessarily limit myself and as concerns some of its phases the invention is applicable to firearms adapted for full automatic or volley firing.

10 The invention relates particularly to a firearm, such as disclosed in my copending applications for automatic firearms, Serial No. 262,818 filed March 19, 1928, and Serial No. 391,675 filed September 10, 1929, wherein the barrel and barrel extension and also the breech slide or bolt move rearward upon recoil to a limited extent and wherein the breech bolt is then permitted to move rearward separate from and to a greater extent than the barrel and barrel extension, being returned to its forward locked position automatically. The separate rearward movement of the breech bolt effects the extraction and ejection of the cartridge shell, effects the 25 cocking of the firing mechanism and effects the transfer of a cartridge from the magazine to the firing chamber.

One of the objects of the present invention is to provide an improved means for insuring a proper relative timing of the recoil and counter-recoil movements of the barrel extension and the breech bolt.

A further object of the invention is to provide an improved mechanism for holding the breech bolt in its rearmost position after the last cartridge in the magazine or clip has been fired.

Further objects of the invention will be apparent from the following specification and claims.

In the accompanying drawings I have shown the embodiment of the invention which I now deem preferable but it will be understood that the drawings are intended for illustrative purposes only and are not to be construed as defining or limiting the scope of the invention, the claims forming a part of this specification being relied upon for that purposes.

50 Of the drawings:

Fig. 1 is a right side view of a firearm embodying the invention.

Fig. 2 is an enlarged fragmentary longitudinal sectional view taken from the right.

Fig. 3 is a transverse vertical sectional view 55 taken along the line 3-3 of Fig. 2.

Fig. 4 is a view similar to Fig. 2 but showing the parts in different relative positions.

Figs. 5, 6, 7 and 8 are enlarged fragmentary views which are partly diagrammatic and 60 which show the action whereby the barrel extension and breech bolt are maintained in proper timed relation.

Fig. 9 is an enlarged fragmentary longitudinal sectional view showing cartridge supply mechanism and associated parts. 65

Fig. 10 is a rear view of the cartridge clip, this view being on the same scale as Fig. 9.

In the drawings Fig. 1 is a right side view of the gun as a whole, the receiver being 70 shown at 1, the barrel at 2, the breech bolt at 3, the breech cover at 4, the stock at 5, the barrel jacket at 6, and the barrel cover at 7.

As shown in Figs. 2 and 4, the receiver 1 is connected at its front end with the rear 75 end of the barrel jacket 6, a threaded connection being shown. The receiver 1 is provided with parallel longitudinal side walls 8, 8 which are adapted to receive between them the barrel extension 9 and to 80 serve as guides controlling the longitudinal movement thereof. At the rear the receiver 1 is connected with the reaction spring tube 10 which extends rearward and downward. Connected with the receiver at the bottom 85 thereof is a member 11 having a substantially rectangular cartridge opening 12 therein, this opening being in register with a similar opening in the top of the receiver. The member 11 has the trigger guard 11^a formed 90 thereon, and it also supports certain operative parts of the gun as will presently appear.

The barrel 2 and the barrel extension 9 are suitably connected together as by threading and the barrel is provided at the rear 95 with the usual cartridge chamber 13. The barrel extension is formed to receive the breech bolt 3, and it is further formed with suitable guide portions adapted to fit between and be guided by the side walls 8, 8 100

of the receiver. The relationship between the barrel extension and the receiver is clearly shown in Fig. 3. Upon assembly the barrel and barrel extension are inserted from the rear, the barrel extension being guided between the walls 8, 8. When the mechanism is completely assembled the barrel and barrel extension have only a limited movement with respect to the receiver. The barrel extension 10 is provided with a relatively large bottom opening adapted to register with the cartridge opening 12 and to permit the passage of cartridge clips therethrough as will be presently explained. At the rear of the said 15 opening the barrel extension is formed with a forward facing shoulder 14.

Fig. 2 shows the breech bolt 3 in its normal relationship with the other parts of the gun. The main body of the breech bolt is 20 preferably of unitary construction, having all of its parts rigidly maintained in fixed relation to each other. At the sides of the breech bolt near the front are guide flanges 15 which normally enter and loosely fit guide 25 grooves 16 in the side walls of the barrel extension. The breech bolt 3 is held in its forward position by means of a strut 17 pivotally connected with the rear portion of the said bolt. The rear end of the strut 17 engages a 30 plunger 18 which is slidable in the reaction spring tube 10. The reaction spring 19 in the said tube serves to push the plunger 18 forward and thus through the strut 17 serves to push the breech bolt 3 forward and yielding 35ingly hold it in its forward position.

The breech bolt 3 has a downward projecting lug 20, the rear face of which normally engages the shoulder 14 on the barrel extension. When the lug and the shoulder are 40 thus engaged the breech bolt and barrel extension are positively locked together in the proper position for firing. Upon recoil unlocking is effected by causing the rear part of the breech bolt to move transversely or 45 diagonally with respect to the direction of movement of the barrel extension. The front end of the bolt moves directly rearward, being guided by the grooves 16, and the bolt is thus given an angular or tilting movement about a transverse axis near the front 50 end thereof.

Figs. 2 and 4 show the breech cover 4 in its operative relationship with the other parts, 55 but it will be understood that the said cover is readily removable. The breech cover 4 has at the front a downward projection 21 which is adapted to engage an upward projection 22 on the breech bolt as shown in Fig. 60 2; the said projections being provided respectively with inclined cam surfaces 23 and 24. When the two projections are in engagement as shown the breech bolt and barrel extension are held in their described 65 locked relationship, it being impossible for

the lug 20 to become disengaged from the shoulder 14.

As already stated the breech bolt and barrel extension are directly locked together when in the firing position. When firing occurs the barrel and barrel extension move rearward under the force of the recoil, and the breech bolt, by reason of the described locked relationship, initially moves rectilinearly in unison with them. Then the rear part of the breech bolt is moved transversely or diagonally upward and rearward until the lug 20 is disengaged from the barrel extension. After disengagement the breech bolt continues to move rearward and the motion of the barrel extension and barrel is stopped.

Mounted in the receiver is a member 25 which I will refer to as an accelerator. The accelerator is pivotally mounted on a transverse pin 26 which extends into bearing apertures in the receiver. The main body portion of the accelerator is curved upward and rearward, having a convex forward facing surface which is adapted to cooperatively engage a flat rearward facing surface near the rear end of the barrel extension. By reason of the engagement of the accelerator with the flat surface of the barrel extension the said accelerator is moved in the counter-clockwise direction until the upper end thereof engages the breech bolt at 27. The timing is such that, when the accelerator engages the breech bolt as stated, the breech bolt has moved rearward sufficiently to permit the flat horizontal surfaces of the projections 21 and 22 to disengage each other, the rear part of the breech bolt then being free to move diagonally upward and rearward along a path determined by the engagement of the cam surfaces 23 and 24.

Continued pressure exerted by the rearward moving barrel extension on the accelerator causes the accelerator to force the rear part of the breech bolt upward and rearward until the lug 20 disengages the shoulder 14. The rearward pressure of the barrel extension upon the accelerator continues and the accelerator now serves to move the breech bolt rapidly rearward, imparting to it a velocity which enables it to move in opposition to the spring 19 approximately to the position shown in Fig. 4, being guided in part by the inner surface of the cover. During its separate rearward movement the breech bolt is guided in part by the before-mentioned flanges 15 which enter grooves 28 formed in the barrel extension. It will be seen that the accelerator serves to transfer the energy of the moving barrel and barrel extension to the said breech bolt, the result being that the movement of the barrel and barrel extension is gradually retarded and finally stopped while the absorbed energy is imparted to the 130

breech bolt to throw it rearward to the position of recoil.

As clearly indicated in Fig. 4 the lower surface of the lug 20 of the breech bolt remains in engagement with the accelerator during the separate rearward and return movements of the breech bolt. Thus the accelerator is held in its rearmost position as indicated. It will be observed that the lower surface of the lug 20 is so inclined with respect to the main body of the bolt that upon angular movement of the bolt it assumes a position parallel with the direction of the separate rearward movement. Thus, the accelerator is held immovable during such movement.

There is provided a stop 29 on the barrel extension which is engaged by the accelerator 25 when the extreme position is reached, the said accelerator being provided with a surface at 30 to engage the said stop. The engagement of the stop with the accelerator prevents further rotative movement of the latter and at the same time a shoulder 31 on the accelerator engages the bottom of the barrel extension.

As soon as the breech bolt reaches its rearmost position as shown in Fig. 4 it is immediately returned in the forward direction by reason of the action of the spring 19 and associated parts. As the breech bolt moves forward the lug 20 releases the accelerator and immediately thereafter the forward facing surface at 27 re-engages the accelerator 35 and causes it to move in the clockwise direction to the position shown in Fig. 2. As the accelerator moves in the clockwise direction the barrel and barrel extension move forward in unison with the breech bolt but at a slower speed. As soon as the parts reach the proper position the cam surfaces 23 and 24 engage with each other, the result being that as the breech bolt continues to move forward it is returned to its locked relationship with the barrel extension. The final movement of the breech bolt in the forward direction carries the barrel and barrel extension with it in locked relationship, thus completely restoring the parts to the relationship shown in Fig. 2.

In accordance with the present invention I provide novel means for maintaining the proper timed relationship of the barrel extension and breech bolt during their recoil and counter-recoil movements, particularly during the latter. For this purpose I provide what I will term a timing cam 32 which is directly connected with or formed as a part of the accelerator. The action of the timing cam 32 and its cooperative relationship with other parts are shown clearly in Figs. 5 to 8.

During counter-recoil movement the accelerator is moved in the clockwise direction, its movement being effected by means of the

forward facing surface at 27 on the breech bolt, as shown in Fig. 5. The timing cam 32 is positioned to project upward into the space between the left hand side of the breech bolt and the left hand wall of the barrel extension. Formed on the said left hand wall of the barrel extension is an inward projecting lug 33 the forward surface of which serves as an abutment adapted to be engaged by the timing cam 32 as shown. The curvature of the cam 32 is such that for all positions of the accelerator and barrel extension, the said cam is in engagement or substantially in engagement with the said lug 33. It will be understood that at the same time the forward facing surface of the accelerator proper remains in engagement with the rearward facing surface of the barrel extension. It will thus be apparent that the combined accelerator and timing cam is held in predetermined relationship with the barrel extension, movement of the barrel extension being possible only when the timing element is correspondingly moved.

The cam 32 retards forward movement of the barrel extension, and the inclination of the cam is such as to make impossible any movement of the cam and accelerator by reason of forward pressure exerted on the cam by the barrel extension. The accelerator and cam are moved only by the forward moving breech bolt as already explained, and it is, therefore, impossible for the barrel extension to move forward too rapidly so as to get out of proper timed relation with the breech bolt. Fig. 6 shows the accelerator and cam moved to an intermediate position by the breech bolt, but the engagement of the cam with the abutment 33 prevents any excess movement of the barrel extension in the forward direction. Fig. 7 shows the accelerator and cam moved to the position where locking is about to take place. The cam has now moved nearly to a position in which it no longer retards the barrel extension, and the barrel extension and breech bolt can move forward in unison to the position shown in Fig. 8.

The breech bolt 3 carries at the right side thereof a handle 34 which may be used to manually operate the mechanism of the gun. It will be understood that upon manual movement the operation of the parts is the same as already described.

Mounted within the breech bolt 3 is a firing pin which is not shown in detail as it does not in itself constitute any part of the invention. This firing pin is adapted to project from the breech bolt from the rear thereof as indicated at 35 and when so projecting it is held by means of a vertically movable sear 36 mounted in the breech bolt. The sear is provided with a downward hook extension 37 adapted to be engaged by the trigger lever as will presently be described.

A spring is provided for normally pressing the sear upward.

The cocking lever is shown at 38, being pivotally mounted on the breech bolt for movement about a transverse axis. When the breech bolt moves rearward as already described the cocking lever is forced against a shoulder 39 on the receiver and it then travels along a surface 40 on the receiver as shown in Fig. 4. The cocking lever in moving from the position shown in Fig. 2 to the position shown in Fig. 4 moves the firing pin 35 relatively rearward into position to be engaged by the sear 36.

It will be understood that as the breech bolt moves rearward it extracts and ejects the shell of the cartridge that has been fired, suitable extracting and ejecting devices being supplied for this purpose. These devices constitute no part of the present invention and are not shown. They may be constructed as disclosed in my copending applications before referred to.

The trigger 41 is pivotally mounted at 42 on the member 11 and projects downward through an aperture in the said member adjacent the guard 11^a. The trigger is provided at the top with a cam surface which engages the bottom face of a lever 43 pivoted at 44 to the member 11. Pivoted to the lever 43 is a hooked link 45 which is adapted to detachably engage the hooked portion 37 of the sear when the parts are in the firing positions as shown in Fig. 2. The link 45 and the lever 43 are both pressed in the counter-clockwise direction by a spring 46. When the trigger is pulled toward the rear the lever 43 is turned in the clockwise direction and the link 45 and the sear 36 are pulled downward to release the firing pin 35.

I have shown a safety mechanism which is in many respects similar to that disclosed in my aforesaid copending application Serial No. 391,675. There is provided a safety lever 47 which is pivotally mounted at 48 on a stud carried by the receiver at the left side. At the forward end of the lever 47 is an upward extension 49 which is adapted to project into the path of movement of the rear end of the breech bolt. The safety lever is further provided with a lug at 50 which is adapted to engage the trigger lever 43 and prevent movement of the trigger. The lever 47 can be operated by means of the manually operable lever 51 which is pivoted at 52 to the detachable cover 4. The upper end of the lever 51 carries a finger piece 53 which is exposed at the left of the cover and the lower end is detachably engaged with the lever 47 as shown. By manually operating the lever 51 the lever 47 can be moved in the counter-clockwise direction from the position shown in Figs. 2 and 4 and when so moved it locks the breech bolt and the trigger, thus effectively preventing firing.

As already stated, openings are provided in the receiver and in the barrel extension which register with the cartridge opening 12 and it will therefore be seen that there is in effect a cartridge opening which extends entirely through the fire-arm from top to bottom thereof. This opening is adapted for receiving cartridge clips 54 which are passed through the fire-arm from top to bottom.

Each clip 54 is open at the top, bottom and front, but is closed or substantially closed at the rear. As shown most clearly in Figs. 9 and 10 each cartridge clip 54 is formed of sheet metal and is preferably of such width as to hold two rows of cartridges as shown. The side walls of the clip 54 are bent inward slightly at the top and bottom as shown at 55, to assist in holding the cartridges in place, and the said side walls are also provided with inward bent ribs 56 to enter the grooves in the cartridges to also assist in holding them in place. The rear wall of the clip 54 is preferably bent to form a rearward projecting rib 57 and the rear portion of this rib is partly cut away to form at least one opening 58. Preferably the clip is reversible so that it can be inserted in the firearm either side up and in this case there are two similar openings 58 similar to each other and similarly located with respect to the corresponding end of the clip.

Mounted within the cartridge opening 12 is a vertically movable follower 59 which is adapted to engage the cartridges at the lower end of the clip 54, and which is adapted to enter the clip and press the cartridges upward as they are successively removed at the top. The follower 59 moves upward approximately in parallelism and it is actuated and controlled by a link mechanism similar to that disclosed in Patent No. 549,345 issued November 5, 1895 to John M. Browning. This mechanism comprises a curved link 60 pivoted at 61 to the rear end of the follower, and pivoted at 62 to the main frame or receiver of the firearm at the front of the opening 12. Pivoted to the link 60 between the ends thereof is a second link 63, one end of which presses against the follower 59. The other end of the link 63 is curved and engages a suitable fixed abutment 64. A spring 65 tends to move the link 60 in the clockwise direction, thus pressing the follower 59 upward. The curved end of the link 63 is so shaped that the said link serves to support the forward portion of the follower 59 and to cause it to move upward in substantial parallelism.

With the loaded clip 54 in place as shown in Fig. 4, the follower 59 and also the links 60 and 63 are in their lowermost positions. Mounted on the member 11 is a spring pressed pivoted detent 66 which enters the lower opening 58 in the clip, thus preventing the

clip from being moved upward as the result of pressure exerted by the follower 59.

Forward movement of the breech bolt from the position shown in Fig. 4 removes the 5 foremost cartridge from the clip and advances it into the chamber 13 of the barrel and effects firing thereof. Upon pulling the trigger firing then takes place and the recoil 10 action of the breech bolt and other parts follows in the manner already described. Upon each return movement of the breech bolt a cartridge is withdrawn from the clip and advanced into the firing chamber, this action continuing until the clip is entirely empty.

15 At the rear of the cartridge opening 12 there is provided a vertically movable stop 67 which is normally held in its lowermost position by means of a spring 68. These parts are shown particularly clearly in Fig. 9. The 20 stop 67 is so constructed that when moved upward its upper end lies in the path of movement of the breech bolt and thus serves to retain the breech bolt in its rearmost position as clearly shown in Figs. 4 and 9. Carried 25 by the stop 67 is an element 69 which normally projects forward into the path of upward movement of a lug 70 on the follower 59. These parts are so related that the follower engages the said element 69 after the last cartridge 30 has been removed from the clip and moves the said element 69 and the stop 67 upward. The result is that the stop 67 is positioned in the path of movement of the breech bolt and holds the breech bolt in its rearmost 35 position as already stated. It will be understood that the breech bolt exerts sufficient pressure on the stop 67 to hold it in its upper position even though the follower is moved downward. The breech bolt can be 40 released after the insertion of a loaded clip by pulling backward on the handle 34 so as to release the breech bolt on the stop 67.

Preferably the element 69 projects through the upper opening 58 in the clip, the opening 45 being of sufficient length to permit the necessary movement of the said element. The said element 69 is pivoted and is normally held in its projecting position by a spring pressed plunger 71.

50 Fig. 9 shows the procedure of replacing an empty cartridge clip with a loaded one. After the last cartridge in a clip has been fired the stop 67 holds the breech bolt 3 in its retarded position as already described. A loaded 55 clip is then put in place at the top and is pressed downward into the cartridge opening. The loaded clip engages the empty one and pushes it downward, the spring detent 66 being pushed back out of the way. The empty 60 and loaded clips as they move downward push the element 69 rearward and it finally projects into the upper opening 58 in the loaded clip. As the loaded clip moves downward 65 the follower 59 is also moved downward to

its lowermost position as shown in Fig. 4. What I claim is:

1. A firearm of the class described comprising in combination, a receiver, a barrel and barrel extension movable upon recoil rearward relatively to the receiver, a rearward movable breech bolt normally in locked engagement with the barrel extension, means operative during recoil for unlocking the bolt from the extension and operative during 70 counter-recoil for restoring the locked relationship, an accelerator pivoted to the receiver for movement about a fixed transverse axis and connected with the barrel extension for movement therewith, the said accelerator serving upon recoil to move the breech bolt rearward separately from the barrel extension, and a cam on the accelerator engaging the barrel extension to retard forward movement thereof during the counter-recoil movement of the bolt, the inclination of the said cam being such as to prevent turning thereof by forward pressure exerted thereon by the barrel extension. 75

2. A firearm as set forth in claim 1, wherein 90 the breech bolt engages the accelerator to hold it in its rearmost position during the separate rearward and forward movements of the bolt, and wherein the cam on the accelerator engages the barrel extension when the accelerator is in its rearmost position. 95

3. A firearm as set forth in claim 1, wherein 100 in the accelerator, prior to moving the breech bolt rearward, serves as a part of the unlocking means and moves at least a portion of the breech bolt transversely with respect to the barrel extension. 105

4. In a firearm of the class described, the combination of a receiver having a cartridge opening extending vertically therethrough for receiving at the top a cartridge clip which is open at the top, bottom and front and closed at the rear, a breech bolt movable rearward upon recoil and automatically returned to its normal position, a follower on 110 the firearm adapted to enter the cartridge clip at the bottom and move cartridges successively upward out of the clip into the path of return movement of the bolt, and a stop mechanism at the rear of the cartridge opening adapted to be engaged by the follower and moved upward into the path of return movement of the bolt after the last cartridge has been removed from the clip, the said stop mechanism including an element yieldable 115 to permit a loaded clip to be inserted at the top and the empty clip to be discharged at the bottom. 120

5. A firearm as set forth in claim 4, wherein 125 in the stop mechanism comprises a substantially vertically movable plunger and an element horizontally pivoted on the plunger and normally projecting into the path of movement of the follower.

6. In a firearm of the class described, the 130

combination of a receiver having a cartridge opening extending vertically therethrough, a cartridge clip adapted to enter the cartridge opening at the top, the said clip being open at the top, bottom and front and having a small opening in its rear wall, a breech bolt movable rearward upon recoil and automatically returned to its normal position, a follower on the firearm adapted to enter the cartridge clip at the bottom and move cartridges successively upward out of the clip into the path of return movement of the bolt, a stop at the rear of the cartridge opening adapted to be moved upward into the path of return movement of the bolt, and an element connected with the stop and normally projecting through the opening in the rear wall of the clip so as to be engaged and moved upward by the follower when the last cartridge has been removed from the clip, the said element being yieldable to permit the empty clip to be discharged at the bottom and a loaded clip to be inserted at the top.

7. In a firearm of the class described, the combination of a receiver having a cartridge opening extending vertically therethrough, a cartridge clip adapted to enter the cartridge opening at the top and similarly formed at both ends so as to be reversible, the said clip being open at the ends and at the front and also having its rear wall cut away to a limited extent, a breech bolt movable rearward upon recoil and automatically returned to its normal position, a follower on the firearm adapted to enter the cartridge clip at the bottom and move cartridges successively upward out of the clip into the path of return movement of the bolt, a stop at the rear of the cartridge opening adapted to be moved upward into the path of return movement of the bolt, and an element connected with the stop and normally projecting through the rear wall of the clip with the clip in either of its relatively reversed positions so as to be engaged and moved upward by the follower when the last cartridge has been removed from the clip, the said element being yieldable to permit the empty clip to be discharged at the bottom and a loaded clip to be inserted at the top.

8. A firearm as set forth in claim 7, wherein the cartridge clip has two similar openings in its rear wall and is thus adapted to be reversed in position.

55 9. A firearm as set forth in claim 7, wherein the cartridge clip has two similar openings in its rear wall and is thus adapted to be reversed in position, and wherein there is provided a detent adapted to enter the opening which is not entered by the yieldable element on the stop.

In testimony whereof I have hereunto set my hand this 20th day of January, 1931.

65 JONATHAN EDMUND BROWNING.
